This invention relates to heat exchangers and, more particularly, to a novel anti-icing arrangement for preventing freezing of drained heat exchangers of air condensing apparatus.

There are known to the art so-called air condensing units which include a mixing condenser, a circulating pump connected thereto, a surface heat exchanger, and pressure reducing means such as a water turbine. The circulating pump draws water from the mixing condenser and feeds it to the surface heat exchanger, where the relatively hot withdrawn water is cooled by the action of atmospheric air, and the thus cooled water is returned by the pressure reducing apparatus to the mixing condenser. In the latter it is admixed with steam entering the mixing condenser, as from the exhaust of a steam turbine, and thereby reheated.

Air condensing units of this type are used in conjunction with steam turbines of steam power plants, and are so designed that they can effectively cool the cooling water, at relatively high summer temperatures and under full load, to a temperature suitable for the steam turbine operation. A heat exchange surface which is adequately sufficient for cooling of the water at relatively high summer temperature and at full load is, of course, too large for use under conditions of winter temperatures and partial loads.

For this reason, the cooling efficiency of air condensing apparatus is regulated in various manners. In the more usual case, a regulating method is employed in which portions of the heat exchange apparatus are operatively disassociated from the water circulating system. The water present in the thus disassociated portions of the heat exchange apparatus is discharged into an appropriate receptacle so as to prevent freezing of the water remaining in the still operating parts of the heat exchanger.

However, the air in that area of the drained heat exchange apparatus normally occupied by water is above and in contact with the drain pipes, as well as being in contact with the other water which circulates in the still operating area of the air condensation apparatus or is retained therein. The temperature of the water is substantially higher than the air temperature in that area of the drained heat exchanger normally occupied by water. As a consequence, the air is maintained in a state saturated with water vapor due to such contact.

As stated, the heat exchangers are usually drained during the cold winter weather when the air temperature drops below the freezing point, as at this time the heat exchange surface necessary for proper operation is greatly reduced. Thus, both the drained parts of the heat exchanger apparatus and also the walls of the pipes on the water side are naturally at a temperature below the freezing point.

Under these circumstances, the air in the drained areas of the heat exchange apparatus, and which is saturated with water vapor, freezes on the pipe walls, whose temperature is below the freezing point, thus forming an ice coating on these walls. The water vapor thus frozen out, or extracted, from the air, leaves a vacuum which is then filled with fresh water vapor by way of the drain pipes,

2

so that the air is again saturated with water vapor. As a result, a very heavy ice coating or formation will build up. If the temperatures remain below the freezing point for any length of time, the condition just mentioned will result in the water pipes of the heat exchange apparatus being frozen completely due to the steadily increasing thickness of the ice coating thereon.

It frequently happens, in the operation of air condensing equipment, that a previously drained portion or area of the heat exchange apparatus must be restored to operation when the ambient temperature is below the freezing point. This requires that such drain portion of the heat exchange apparatus, and particularly the water circulation through and substantially unimpeded water circulation is not achieved substantially immediately in all the water circulation system, freezing will occur in those parts of the circulating system where, for any reason, the circulation of water is impeded to any substantial extent. The aforementioned build-up of ice coatings in part or all of the water circulating system may impede the water circulation sufficiently, during the relatively brief time interval required for freezing of the pipes upon the start of water flow therethrough, so that the water flow is blocked. It is therefore necessary, in the interest of safety of operation of the air condensing equipment, to provide an arrangement for preventing the formation of such ice coatings in the exhaust air condensing apparatus.

The present invention is directed to a novel and efficient arrangement for preventing the building up of ice coatings in the water circulating systems of exhausted air condensing apparatus, and this is the principal object of the present invention. More particularly, in accordance with the present invention, a novel air shut-off valve is provided in each of the pipes utilized for draining the heat exchange apparatus. This valve is so designed as to permit the substantially complete draining of water from the heat exchange apparatus, while closing automatically, after the heat exchange apparatus is drained, to prevent seepage of water vapor through the drain pipes back into the heat exchange apparatus. Thereby the building up of the aforementioned ice layers is substantially inhibited.

Accordingly, a further object of the invention is to provide, in heat exchange apparatus including air condensing units having water circulating systems connected by drain pipes to a tank for storage of discharged water, a device for inhibiting freezing of the heat exchanging apparatus and comprising air shut-off valve means in the drain pipe or pipes between the heat exchange apparatus and the usual drain shut-off valves.

A still further object of the invention is to provide such an air shut-off valve means having a primary sealing surface biased to the closed position and a secondary sealing surface within the primary sealing surface and likewise biased to the closed position and located at the lowest point of the primary sealing surface.

Another object of the invention is to provide such an air shut-off valve in which the free cross sectional area of the secondary sealing surface or valve does not exceed $\frac{1}{10}$ of the free cross sectional area of the primary sealing surface or valve.

A further object of the invention is to provide such an air shut-off valve means which is mounted, as a complete unit, in the drain pipe in such a manner as to allow flow through the drain pipe only in a direction from the heat exchange apparatus to the storage tank, while hermetically sealing off any flow in the opposite direction.

In a preferred embodiment of the invention, the drain pipes, rather than being connected directly to the heat exchange apparatus, are connected to a header which has connected thereto a number of heat exchange units.

For an understanding of the principles of the invention, reference is made to the following description of a typical embodiment thereof as illustrated in the accompanying drawings. In the drawings:

FIG. 1 is a somewhat schematic and diagrammatic elevational view of apparatus embodying the invention;

FIG. 2 is a plan view, partly in section, of an air shut-off valve embodying the invention;

FIG. 3 is an axial sectional view through the air shut-off valve shown in FIG. 2; and

FIG. 4 is an enlarged partial sectional view illustrating a detail of FIG. 3.

As shown in FIG. 1, a heat exchanger, such as an air condenser 1, is connected to a water inlet 3 and a water outlet 4 through water chambers 2. Water inlet 3 and water outlet 4 are provided with shut-off devices, such as valves 5 and 6, respectively, by means of which the water circulation through the air condenser 1 can be discontinued so the latter may be disconnected from the water circulating system. Drain pipes 7 are connected to the lines connecting inlet 3 and outlet 4 to valves 5 and 6, respectively, the drain pipes 7 being connected to the lowest points of these lines and discharging into a tank 8 provided in the drain pipes 7 to drain cooling water from the unit 1 into the storage tank 8. In advance of the shut-off valves 9, each drain pipe 7 is provided with an air shut-off valve means 10 embodying the invention and acting to isolate the unit 1 from the water stored in the tank 8.

The detailed construction of the novel air shut-off valves 10 is shown in FIGS. 2, 3 and 4. Referring to these figures, each valve 10 comprises a pair of generally semi-circular flap valves 11 which are pivotally mounted and conjointly provide a valve head or sealing surface of relatively large diameter which is biased to the closing and sealing position by suitable means, illustrated by way of example as counterweights 12. As best seen in FIG. 3, each valve 11 has a bent shape including an upwardly curved inner or straight edge, so that, in the closed position, the major portions of the valves 11 slope downwardly and inwardly. The biasing means is so provided or adjusted that only about one meter of water head is required to open valves 11. Each valve 11 has an aperture at its lowest point, each aperture being controlled by a flexible, such as rubber, flap valve 13 which is arranged to open at a pressure of only a few cm. of water head, so as to provide for drainage of any water remaining above the valves 11 when the latter have been closed by their biasing means when most of the water has been drained.

By the provision of the dual valve arrangements, oriented and biased as shown in the drawings, the desirable result is obtained that, during discharge of water from the unit 1 through the drain pipes 7 in communication therewith, the water is drained almost completely from the unit whereas, on the other hand, the air space of the drained unit is hermetically sealed off from the tank 8 storing the drained water.

The arrangement operates in the following manner. While the unit 1 is in service, the valves 5 and 6 are open so that cooling water may circulate through the heat exchanger 1, and the shut-off valves 9 in the drain pipes 7 are closed. When it is desired to disconnect the unit 1 from the system, the shut-off valves 5 and 6 are closed and the drain shut-off valves 9 are opened. Thereupon, the water in the circulating system of unit 1 and in the pipes connected thereto drains off into tank 8 and, so long as the head of water is above the value necessary to open the valves 11, these valves remain open and the water flows through the now open shut-off valves 9 into the tank 8. As the water is discharged, the water head is gradually reduced so that, when there is less than about one meter of water column above the valves 10, valves 11 close. However, the valves 13 which are provided at substantially the center of each of the valve elements 11, remain opened due to the still existing water head until the latter has been decreased to a value of only a few cm. At this latter value, the valves 13 close

and thus hermetically seal off the tank 8 from the unit 1 so as to prevent water vapor flowing from the tank 8 into the unit 1.

As stated, in a preferred arrangement of the invention, the drain pipes 7 are not connected directly to the unit 1 but preferably are connected to headers, such as 14 and 15, to which may be connected several heat exchanger units.

While a specific embodiment of the invention has been shown and described in detail to illustrate the application of the principles of the invention, it will be understood that the invention may be embodied otherwise without departing from such principles.

What is claimed is:

1. In combination with an apparatus of the type including heat exchanger means, means for circulating water therethrough, a storage tank for drained water, a drain pipe connecting a water circulating system of said heat exchanger means to said tank, and a drain shut-off valve in said drain pipe, which is closed during operation of the heat exchanger means and is opened to drain the heat exchanger means when the latter is taken out of service: a device for preventing freezing of said heat exchanger means when the latter has been drained, said last-named device comprising air shut-off valve means in said drain pipe at the side of said drain shut-off valve opposite from said tank and said air shut-off valve means automatically opening in the direction of flow in said drain pipe toward said tank in response to a pressure head, over said air shut-off valve means, greater than a predetermined value; and biasing means biasing said air shut-off valve means to close when the pressure head in a direction toward said tank is less than said predetermined value.

2. In combination with an apparatus of the type including heat exchanger means, means for circulating water therethrough, a storage tank for drained water, a drain pipe connecting a water circulating system of said heat exchanger means to said tank, and a drain shutoff valve in said drain pipe, which is closed during operation of the heat exchanger means and is opened to drain the heat exchanger means when the latter is taken out of service: a device for preventing freezing of said heat exchanger means when the latter has been drained, said last-named device comprising an air shut-off valve in said drain pipe at the side of said drain shut-off valve opposite from said tank and including a relatively large area primary valve means automatically opening in the direction of flow from said heat exchanger means to said tank whenever the pressure head in said direction of flow exceeds a first predetermined value, means biasing said primary valve means to close when the pressure head in a direction toward said tank is less than said first predetermined value; said primary valve means having a relatively small aperture therethrough; a second valve means, having a relatively small area, controlling flow through said aperture and automatically opening in the direction of flow from said heat exchanger means to said tank, and biasing means biasing said secondary valve means to close when the pressure head in the direction toward said tank is less than a second predetermined value which is substantially less than said first predetermined value.

3. The combination claimed in claim 2, in which the flow area of said aperture does not exceed $\frac{1}{10}$ of the free cross sectional flow area of said primary valve element.

4. The combination claimed in claim 2, including counterweight structure forming said means biasing said primary valve element to the closed position.

5. The combination claimed in claim 2, wherein said aperture is formed at the lowermost portion of said primary valve element.

6. The combination claimed in claim 5, in which said secondary valve element is a flap valve of flexible material resiliently biased to the closed position, and located on the underside of said primary valve element.

7. The combination claimed in claim 2, in which said drain pipe is connected between said tank and a header connected to said heat exchanger means and constructed and arranged for connection to other heat exchanger means.
